UNITED STATES PATENT OFFICE

GEORGE A. GAST, OF CHICAGO, ILLINOIS, ASSIGNOR, BY MESNE ASSIGNMENTS, TO JOHN F. MEYER, OF PASADENA, CALIFORNIA

DESIGN FOR AN AMUSEMENT MACHINE CABINET

Application filed April 17, 1933. Serial No. 47,816. Term of patent 14 years.

To all whom it may concern:

Be it known that I, GEORGE A. GAST, a citizen of the United States, residing at Chicago, in the county of Cook and State of Illinois, have invented a new, original, and ornamental Design for an Amusement Machine Cabinet, of which the following is a specification, reference being had to the accompanying drawing forming a part thereof in which the figure is a perspective view of an amusement machine cabinet showing my new design.

I claim:

The ornamental design for an amusement machine cabinet as shown.

GEORGE A. GAST.
